UNITED STATES PATENT OFFICE.

SILVANUS F. VAN CHOATE, OF BOSTON, MASSACHUSETTS.

ELECTRO-MAGNETIC MOTOR.

SPECIFICATION forming part of Letters Patent No. 286,873, dated October 16, 1883.

Application filed September 4, 1880. (No model.)

To all whom it may concern:

Be it known that I, SILVANUS FREDERICK VAN CHOATE, a citizen of the United States, now residing in the city of Boston, Massachusetts, have invented certain new and useful Improvements in the Mode of Constructing Electro-Magnetic Motors, of which the following is a description, which will enable others skilled in the art to which it appertains to make and use the same, reference being made to the accompanying drawings.

My invention consists in a novel arrangement of electro-magnets and circuit-connections in electrical machines, and either as generators or motors.

In carrying my invention into practical effect, I form two iron or steel rings, preferably hexagonal (although one simple plain ring may be used) on their periphery, as shown at 20 A in Figure 1 and in section at B B in Fig. 2 of the drawings. On each of the six sides of this ring I place a spool or helix of wire, it being attached to the ring by a core-pin of iron or steel, as may be desired, which is secured in a hole bored through the ring, as at 25 a in Fig. 2, while the upper or outer end of said core is provided with a flanged head or projection to hold the spool firmly down, as shown in Figs. 3 and 4, the core-pin being secured to the ring by a dowel-pin, as shown at 30 b b in Figs. 1 and 4. Two of these hexagonal rings, with their spools and cores formed in the same way, are fitted together and secured by screws or otherwise, so as to form one 35 double ring of six spools each, the rings being in perfect metallic contact with each other. The spools of the two rings are arranged diagonally to each other, so as to "break joints," as it were, or form "staggered joints," as 40 shown in Fig. 1—that is to say, the end of the spools on one ring occupy six points in a circle; but when both rings are put together the ends of the spools of the two rings form or occupy twelve equal points of a circle, as seen 45 in Fig. 1. The six spools or helices of one of these rings are connected and coupled up electrically, so that on passing a current of electricity through the wire of the helices all the cores of one ring will give north polarity and 50 all the cores of the other ring will give south polarity, as shown in Fig. 1 by letters N and

S. The flanged heads of the cores of these spools extend or project on one side, as shown at c in Fig. 3. This projection gives direction to the movement of the motor, the poles of the 55 magnets of the outside ring being attracted toward the projecting flanges of the cores of the helices of the inside rings. The current of electricity is permanently closed through the coils or helices of the hexagonal rings when 60 the motor is in operation.

Instead of forming the hexagonal rings into two parts, they may be made of a single piece of iron or steel, and the hexagonal faces may be formed with a planer or otherwise, or a 65 simple round broad ring may be used, the diagonal rows of holes being properly bored out to receive the core-pins, the latter having shoulders at their doweled ends to determine their depth in the ring and prevent crushing 70 the flanges of the spools.

The outside ring or rings of spools or magnets are arranged in a plane even with the inside ring or rings of spools or magnets, the number of the former being double that of the 75 latter. The outside spools are secured to rings or hoops of iron or steel, as may be desired, by round core-pins of the same metal, (marked b, Fig. 4,) and doweled at their exterior ends, as at b, Fig. 1, while the other end 80 of the said cores terminates with a flange or head, d, Fig. 4, which points inwardly directly toward the center or shaft of the system, as shown in Figs. 1 and 2.

It will be observed that there are twelve 85 spools on the outside ring, C, Fig. 1, while there are but six on the inside ring, A, same figure, and that every other spool of the outside ring, C, points to a space where there is no corresponding spool on the inside ring, A, Fig. 90 1. The spools on the two outside rings shown in plan in Fig. 1, and in section in Fig. 2, are arranged so as to form pairs—that is to say, the spool on the lower ring is directly under the spool on the upper ring, while the spools 95 on the inside rings are arranged diagonally to each other, and break joints, as we have before remarked. The outside spools and rings are secured to a circular frame of non-magnetic metal, (marked f, f, Figs. 1 and 2,) while 100 the inside spools and rings may be fastened to the shaft or spindle and made to revolve in

the center of the outside spools and rings when a low speed is required; or the outside rings may be secured to the spindle and made to revolve around the central spools and rings 5 when a high speed is to be obtained, or vice versa, as may be desired.

The two outside rings are not in electrical contact with each other, and their spools do not form **U**-magnets in the usual way by being coupled together in pairs by lateral cross-pieces; but they are connected together in a complete circle by means of the iron or steel rings, and form **U**-magnets along the line of the ring, as shown by the letters **N** and **S** in Fig. 1, where *g h* is one **U**-magnet, and *h i* another, &c., the ring **C** forming a part of all the **U**-magnets in the circle. The spools or helices of the outside rings are coupled and connected up electrically, so that the electric current causes all the cores of the spools on one outside ring to become negatively charged, and all the cores of the spools or helices of the other outside ring to become positively charged; but when the motor is in operation 25 the electric current is not passed through all the helices of each outside ring at the same instant, but only through each alternate pair or every other spool—that is, the current is passed through each alternate helix of one ring in such a manner as to give every second helix-core on one ring a north polarity, and every second helix-core on the other ring a south polarity, while at the same time every other alternate or second helix-core of each 30 ring, without a current being passed through its helix, is caused to assume the opposite polarity to that of the helix-core next to it, and through which the current at the moment is passing; but these polarities in the cores of the two outside rings break joints, as it were—that is, when one helix-core on one ring is 35 made to assume a north polarity the helix-core of the spool directly and laterally opposite on the other ring is made to assume a south polarity.

We have stated that the electric current is only passed through each alternate or second helix of each outside ring at a certain time. The cores of these alternate helices through 40 which the electric current is acting for the moment become charged or magnetic with the desired polarity—say north, as shown at **N**, in Fig. 1—while at the same instant each other alternate core in the same ring, and through whose helix no electricity is passing at that moment, is made to assume a polarity opposite to that produced in the cores of the same ring through whose helices the electric current is acting at the moment—that is to say, the passing of the electric current in a certain direction through each alternate helix of one ring produces a certain polarity in the cores of said helices, while it causes or induces the opposite polarity in the other alternate core on the same ring through whose helix no electric current at the moment is passing, the

said helix remaining neutral, as it were, for the moment.

Motion is given to the motor by shunting or shifting the electric current from one set of 70 helices to another—as, for instance, the electric current is made to act on every other helix in a ring, giving north polarity to these helix-cores, while the other alternate cores not acted on by the current at the moment are made to 75 assume south polarity, and when the electric current is shunted or shifted into the neutral helices, their cores are made to assume north or south polarity, as the case may be, while the cores of the other alternate helices change 80 to the opposite polarity. But it must be understood that when the cores of the helices of an outside ring are caused to assume a north polarity by the action of the electric current, the same agent causes the cores of the helices 85 on the same side of the inside ring to assume a south polarity, as shown by the letters **N** and **S** in Fig. 1, whereby the proper attraction or mutual pull is produced between the various cores of the helices of each ring, which 90 causes rotation of the motor.

The circuit through the helices of the inside ring is never broken, but is kept closed all the time the motor is in motion, thereby giving these helices and their cores the benefit of a more perfect saturation or charge from the effects of the electric current, and consequently increasing their magnetic strength or pull upon the cores of the outside rings to a wonderful extent, besides keeping the circuit 95 through the battery or the coils of the dynamo-electric generator permanently closed, and thereby aiding the working and increasing the power of the same.

The power of my motor is augmented by increasing size and number of helices and **U**-magnets on the rings, and also by multiplying or increasing the ring system and magnets of the inside and outside system of rings and magnets.

The drawings are half size, and made from an actual working-machine.

Fig. 1 represents a plan of the arrangement of the spools or helices, together with the outside ring **C** and inside ring **A**, while **D** represents the edge of the outside supporting case.

Fig. 2 is a sectional view, showing the spools or helices in pairs, and also the outside case **j j** and outside rings **e e** and inside rings **B B** 120 and part of the shaft or spindle.

Fig. 3 represents an end view of one of the spools or helices; and Fig. 4 is a side view, with their flanged heads **d** and **e** and projecting pin **b**. The outside rings are secured to the frame or outside case **f** by screws marked **k**, while the inside ring or rings are secured to the face-plate **f** of the case by screws marked **l l**. The wires which connect the helices of the inside rings are secured by screws and insulation-plugs at **m m**, Fig. 2. The wire connecting with all of the helices on the outside

rings comes out through the spindle at *n*, and is connected with a continuous band or ring, to be presently described, upon which ring bears a spring connected with one pole of the generator. The terminal *n* corresponds to the terminal *l* in the diagram Fig. 11. The two terminals of the two alternate sets of helices in the two rings are indicated at *o o*, and each of said terminals is connected with one of the two sides of a commutator or circuit-changer, as will be presently described. These two terminals correspond to the connections *k' n'* of the diagram Fig. 11, and, as before explained, and as indicated in Fig. 11, are connected each to alternate helices in both rings.

Fig. 5 is a side elevation of the motor, showing the main drum or case at *F* and the two supports or standards at *G G*, while *H* is a pulley, and *p p* set-screws and taps to hold the same, and by means of which various sizes of pulleys may be fitted to the shaft at pleasure. The base is marked *I*, while *J* is a general side view of the shunt or commutator and its supporting-arms. The ingoing wire to the inside ring of helices is marked *q*, and the ingoing wire of the outside ring of helices is marked *r*, while *K* is a resistance arrangement in section to regulate the speed of the motor.

Fig. 7 is an end view of the shaft and commutator, while Fig. 6 is a side view and Fig. 9 a plan view, showing the two springs connected to the generator.

At *s*, Fig. 6, is indicated the connection to the continuous ring for the terminal *n*, connected to all the helices of the outside rings, upon which ring bears one of the springs *e'*, while at *t t* are the connections to the two sides of the divided or shifting commutator for the two separate terminals *o o*, upon which commutator bears the other spring *e'*. These two springs *e' e'* are connected, as before intimated, the one with the positive and the other with the negative pole of the generator. The divided commutator-ring is constructed, as shown in Fig. 6, of two metallic insulated rings with overlapping projections, so that the terminals *o o* are alternately connected with the spring-bearing on said commutator-ring. The two wires *u' u'* connect at one end with their respective screw-cups *v v* underneath the base, while the other ends connect with the screw-shaft *w* and the rod *x*. The screw-cups *v v* are the main cups of the machine, and serve for the connection of the wires leading from the battery or other generator if the machine be used as a motor, or to the work if the machine be used as a generator. The screw-shaft *w* and rod *x* are made of a material of great resistance to the passage of the electric current. The material which I prefer to employ is made by combining copper, arsenic, and chloride of sodium in the proportions of approximately five to six parts of copper, two to three of arsenic, and chloride of sodium about equal in bulk to the other substances, the whole being fused in a sealed crucible, as I have described

in another application. Other suitable highly-refractory materials that are of high resistance to the electric current might be used in place of the material specified. When the movable tap *y* descends, by the turning of the thumb-screw *z*, below the point of insulation on the rod *x*, (marked *a'*), the current from the generator or source passes through wires *u' u'*, and along screw-shaft *w* and tap *y* and rod *x*, and onto screw-cup *v* at the right, and as the current to and from the generator to the helices of the motor also connects at the screw-cups *v v* the current is thus shunted to a degree more or less corresponding to the position of the nut *y*, and the speed of the motor is decreased or increased accordingly, and when the tap *y* is brought up above the point *a'*, the circuit at that point is opened and the shunt ceases to act. When the tap *y* descends into contact with the metallic sleeve, in which the end of the rod *w* rests, it completely shunts the current from the motor by making direct connection between the wires *u' u'* without compelling the current to pass through the resistance-rod. The broad idea of the two rods and the traveling nut to form the resistance is claimed in another application for patent filed by me. The claims in the present case are made to the improved construction, wherein the nut passes out of connection at one extreme of its movement and makes a short circuit at the other extreme, and also the arrangement of a resistance device constructed to offer a variable resistance, in the manner described, in a shunt around the motor for the purpose of varying the speed of the motor.

Fig. 8 is a front elevation of my motor, *L* being the side of the revolving case, and *M* the standard or support. *N* is the base, and *O* the resistance or shunt for regulating the speed, while *b' b'* and *c' c'* are the wires connecting the spools or helices. *P* is the rack frame or support for the commutator or shunt contacts, *d' d'* being screws to regulate the pressure of the contacts, and *Q* the frame to support the rack, while *R* is a tangent-screw and connection with the rack-support, arranged to oscillate the rack-frame by turning the thumb-screw *d'*.

Fig. 9 is a plan of the commutator or shunt, showing its supporting-arms, the contact-pieces *e' e'*, and their supporting-arms.

Fig. 10 is a plan of the inside ring flattened out like a band or ribbon, and showing the two rows of helices of six each and the manner of connecting the wires. It will be noticed that all the helices or magnets on one side give positive polarity, while all the magnets on the other side give negative polarities, as indicated by the letters *N S*. These two rows of magnets are marked numerically from 1 to 12, and they may be distinguished also by the elongated flanges or heads of their core-pins. In this figure (Fig. 10) the diagonal or straddle-joint arrangement of these helices or magnets is plainly shown. The spools or helices shown in dotted lines in Fig. 10 repre-

sent the relative position of each alternate helix of the outside ring. There would be a like spool or helix immediately over each one of the helices or magnets with the elongated 5 core-heads of the inside ring; and when, by the movement of the motor in the direction of the arrows, these spools or magnets arrive perpendicularly over the magnets of the inside ring they are said to be at their "dead-centers," and the current is then shifted or shunted 10 from them to the next alternate helix—as, for instance, from 1 to f' , and from 7 to g' , and so on through the whole series—while the helices from which the current has just been 15 shifted remain neutral until they arrive at the center points between the magnets or helices of the inside ring, when the current is again shifted or shunted through them, which again causes a magnetic pull between them and the 20 magnets of the inside ring; but it must be noticed that when the magnets or helices of the outside ring arrive at the point of dead-center, as it were—that is, the moment of shifting or shunting the current—the cores of the 25 outside ring, which are approaching the cores of the inside ring, have opposite polarities from those of the inside ring. This produces attraction between the two systems of magnets; but the moment the magnets of the outside ring arrive at their dead-centers, the current being shifted or shunted, they are caused 30 to assume the same polarities as the magnets of the inside ring. This produces repulsion between the two systems, and prevents the 35 magnets of the inside ring from holding fast those of the outside ring, and instead of the magnetism holding the cores together and forming a so-called "dead-center" it helps to push the two systems of magnets apart, and 40 so aids or increases the strength of the motor. The connecting-wire h' commences at the outside layer on spool 1, Fig. 10, and forms the six helices on the left-hand side of the figure, and comes out at the inside layer on spool 6, 45 and then passes around and enters the inside layer of spool 7 at the right hand, and so on through the six helices on that side, and out at the outside layer of helix 12, where it is marked i' .

50 Fig. 11 represents the manner of forming the loops or electrical circuits through the helices of the outside rings. Starting at j' and going in the direction of the arrows, an embranchment is made at k' , where the left-hand wire incloses six alternate helices (marked 55 1) of one of the first outside rings, while that to the right incloses six alternate helices (marked 2) of the other or second outside ring; but when the current enters at the terminal m' it divides at n' , passing to the left through the other six alternate helices of the first outside ring, while the right passes through each other alternate six helices of the second outside ring, and at l' the current is 60 65 conveyed into one conductor. The alternate pull or attraction and repulsion between the

two systems of magnets is produced by changing the current from o' to j' , and from o' to m' , the system of the inside rings being coupled up in tension, while the system of the outside 70 rings are coupled up in multiple arc.

I have now fully and clearly explained my invention, so that with the drawings, which represent exactly a working-machine, I presume any person skilled in the art of electricity 75 can construct and operate it without any difficulty whatever.

What I claim as my invention is—

1. In an electro-magnetic or magneto-electric machine, two circular rows of electro-magnetic helices of opposite polarity, whose cores project radially from a common ring or hub of magnetic material, and which are arranged with the poles of one row or series opposite the spaces between the poles of the adjoining 85 row, substantially as described.

2. In an electro-magnetic or magneto-electric machine, an outer ring or casing of non-magnetic material, to the inner side of which are secured two independent rings of magnetic 90 material, each provided with a series of magnetic cores projecting inwardly on radial lines, substantially as described.

3. In an electro-magnetic or magneto-electric machine, two parallel rows of electro-magnetic helices whose cores project inwardly on radial lines from two independent rings of magnetic material, the alternate helices of each ring being connected in tension or series, and each set connected independently to the commutator, substantially as described, so that each set of alternate helices in each ring may 95 be independently and successively charged.

4. In an electro-magnetic or magneto-electric machine provided with two independent 105 rings of magnetic material, each carrying electro-magnetic helices whose cores project inwardly on radial lines, circuit connections from one set of alternate helices in each ring to one side of a shifting-commutator, circuit-connections from the other set of alternate helices to the other side of said shifting-commutator, and an unbroken connecting-ring on the commutator-shaft, to which are joined the free ends 110 of the wires of the several sets of helices, substantially as described.

5. In an electro-magnetic or magneto-electric machine, two inner parallel rows of helices of opposite polarity, arranged so that the poles of one row or series are opposite the spaces 120 between the poles of the other row, in combination with two outer parallel rows, the alternate helices of each of which rows are connected in two sets and in series to the commutator, and whose poles are arranged on lines 125 parallel to the shaft of the machine, substantially as described.

6. In an electro-magnetic or magneto-electric machine, an inner ring or hub carrying two parallel rows of radially-projecting electro-magnets, the poles of the two rows being 130 of opposite polarity and arranged to break

joint, in combination with two outer inwardly-projecting parallel rows, the alternate helices of which are connected in series or tension in independent circuits, substantially as described, to a shunting-commutator, whereby said sets of alternate helices may be connected independently and successively to the outside circuit, substantially as described.

7. In an electro-magnetic motor, two parallel rows of helices of opposite and constant polarity, arranged to break joint, substantially as described, in combination with two parallel and opposing rows of helices of double the number of said first row, the cores of which are secured to independent supports or rings of magnetic material, and which are charged in the operation of the machine, the alternate ones successively in sets with magnetism of the same name, substantially as described, so as to produce in each magnet changes of polarity by direct charge and by inductive charge from the charged adjoining magnet, substantially as described.

8. In an electro-magnetic motor, a series of electro-magnetic helices whose cores are connected to a common plate or base of magnetic material, independent circuit-connections from the alternate helices, and means whereby the alternate helices may be alternately connected to an electric generator, so that the core of each helix is alternately magnetized by the direct action of its own helix and by magnetic

induction from the core or cores of its adjoining helix or helices.

9. In an electro-magnetic motor operated by reversals of magnetic polarity, a series of electro-magnetic helices whose cores are connected to a common plate or support of magnetic material, independent circuit-connections from the alternate coils of the series, and means whereby said alternate sets may be connected alternately or successively to a generator, so as to produce change of polarity by direct charge and by induced magnetic charge from the core of adjoining helices.

10. The combination, with an electric motor, of a shunting-switch, constructed in the manner described, to variably shunt the motor by means of a sliding nut or contact sliding upon a rod of resistance material, as and for the purpose set forth.

11. The combination, with an electric motor, of the shunting-switch, constructed in the manner described, and serving to break the shunt at one extreme of its movement to completely short-circuit the motor at its other extreme, and in intermediate positions to interpose a resistance varying with its distance from an extreme point of movement.

S. F. VAN CHOATE.
